ABSTRACT

For coiling a strip-formed material issuing from an extruder, a hollow drum is provided against the inner wall of which the extruded material is fed and which rotates at a speed substantially the same as the speed of the extruded material. Within the outer drum is an inner drum which is stationary or rotates independently of the outer drum. When the supply of material suddenly ceases, the material coils around the second drum without being subjected to damaging strains.

METHOD OF COILING STRIP-FORMED MATERIAL AND A MEANS FOR CARRYING OUT THE METHOD

BACKGROUND OF THE INVENTION

1. Field of the Invention

The present invention relates to a method of coiling strip-formed material, by which is meant wire, strip and tubes, and a means for carrying out the method. The invention is particularly valuable for coiling material in hydrostatic extrusion, which is a method in which the manufactured product leaves the press at a great speed and suddenly stops at the end of the pressing cycle. It is particularly suitable for coiling-thin-walled tubes, which are easily deformed.

2. The Prior Art

Strip-formed material can be gathered up in stationary barrels or on rotating drums. When it is gathered in stationary barrels, the material will be rotated one turn around its own axis for each turn in the barrel. For thin wire this causes no inconvenience or problems. For material with a cross section which is not round or tubes, this rotation around the longitudinal axis cannot, as a rule, be tolerated. The material must be coiled on a rotating drum.

In hydrostatic extrusion a strip-formed product, wire, profile or tube, is shaped with the desired cross section since the material in a billet, which is enclosed in a pressure chamber, is subjected to a high hydrostatic pressure and in this way pressed out through an opening in a die. The shaped product leaves the die at a high speed, which may be of the order of 15 m/sec. when manufacturing copper tubing. The tube length which can be obtained from a billet depends on the size of the billet and the cross section of the tube and can be from 300 to 400 metres. The pressing process is interrupted before the billet is completely consumed. When the pressing is interrupted, the material flow through the die ceases almost instantaneously. This circumstance makes it difficult to coil the product especially when this is a tube which is easily deformed. Known coiling devices with a rotating drum of known kind must be stopped exactly when the extrusion ceases, in order to avoid a jerk or stretching of the product which causes damage. This refers particularly to extrusion of thin-walled tubes.

SUMMARY OF THE INVENTION

According to the invention the problem is solved by inserting the product, a rod, wire or a tube, tangentially into a first hollow drum, the inner surface of which has a peripheral speed which is substantially the same as the speed of the incoming product. The product is wound up inside the drum, thus on an inner coiling surface. Inside this drum there is a second drum having an outer coiling surface. This drum is rotatable independently of the first drum. It is normally stationary when a product is wound up in the first drum. When the extrusion is finished and the supply of the press product suddenly ceases, the product is stretched because of the rotation of the first, outer drum and will thus be coiled up on the inner drum without being subjected to damaging strains. Thus, the rotation of the outer drum does not have to be synchronized with the pressing. A rapid braking is not necessary. When, after the extrusion, the product has been separated from the residual billet remaining in the pressure chamber, the part of

the product which is between the drum and the press is wound on by putting the second, inner drum in rotation.

The invention also relates to a means for carrying out the method. Said means comprises a first hollow rotatable drum, having an inner coiling surface, and a second drum, having an outer coiling surface. The second drum is arranged inside the first drum and is rotatable, as a rule, for winding on the last part of a press product.

10 The equipment of course comprises driving devices and handling devices of various kinds.

BRIEF DESCRIPTION OF THE DRAWING

The invention will be further described with reference to the accompanying drawings. FIG. 1 shows in section equipment in which the inner drum with wound-on material is lifted out of the outer drum when a coil of material is to be removed. FIG. 2 shows equipment in which a coil of material is deposited on a transport car. FIG. 3 shows in a larger scale supporting member for a coil in the embodiment of FIG. 1.

DESCRIPTION OF THE PREFERRED EMBODIMENT

25 In the figures, 1 designates a conical hollow drum having an inner coiling surface 2. It is supported by a disc 3 with a hub 4 and is rotatably mounted by bearings 7 to rotate around a pin 5, which is fixed to the floor 6. The drum is driven by a motor 8 through the gear wheel 9 on the motor shaft 10 and a gear wheel 11 on the hub 4. Inside this drum there is a second drum 15 having an outer coiling surface 16. The drum is provided with discs 17 and 18 and at its lower part with a hub 19. It is mounted on the pin 5 by bearings 20 and 30 is driven quite independently of the drum 1 by a motor 22 which is connected to the drum by means of a gear drive having a gear wheel 23 on the motor shaft 24 and a rim gear 25 on the hub 19. In the disc 18 a number of collapsible supporting members 26 are mounted. 35 The inner drum 15 can be lifted out of the outer drum by means of a lifting device, shown as a lifting cylinder 27 with a lifting bar 28 which is connected to the disc 17. Between a plate 29 on the bar 28 and the disc 17 is a bearing 30. Thus, the drum can rotate in relation 40 to the bar 28 in the position shown as well as in an elevated position. A car 31 running on rails 32 can be pushed in below the drum 15 when this is in its elevated position. A guide tube 33 for a press product 34 is located and shaped in such a way that the press product 45 is inserted tangentially into the outer drum 1.

The supporting member 26 is shown in a larger scale in FIG. 3. It is journalled upon a pin 75 in a slot 76 in the bottom disc 18. It is locked in the position shown by means of latch 77 journalled upon a pin 78 between 55 two brackets 79. This latch is operated by an operating cylinder 80 which is fixed to the bottom disc 18 and attached to the latch 77 by means of its operating rod 81. When the latch 77 is withdrawn by the cylinder 80, the coiled product 34 will tilt the member 26 within the slot 76 and fall down upon a car 31 moved into a position 60 below a lifted drum.

In FIG. 2, 41 designates a conical drum having an inner coiling surface 42. It is suspended in a conical disc 43 which is rotatably mounted in a ring 44 by a bearing 45. The ring 44 is suspended on the underneath side of the floor 46. The drum is driven by a motor 47 through the V-belt 48 running over the grooved pulley

49 on the shaft 50 of the motor 47 and over the scored pulley 51 of the drum 41. Inside the drum 41 is a second drum 52 having an outer coiling surface 53. This drum is suspended with the discs 54 and 55 on a shaft 56 which is mounted in the hub 57 in the floor 46 by bearings 58. It is connected to the driving motor 59 by means of the gear wheel 60 on the motor shaft 61 and the gear wheel 62 on the shaft 56. The drum 52 is provided at its lower part with a number of radially manoeuvrable coil supports 65 which are mounted in slits 66 in the drum 52 and in slits 67 in the ring 68, which is suspended in the disc 55. The supports 65 can be operated radially between the position shown in the figure and a retracted position by means of an operating device 69 such as a hydraulic cylinder. A press product 70 is inserted tangentially into the drum 41 by means of a guide tube 71 which passes the opening 72 in the floor 46 and the ring 44. Below the drums a transport car 73 for a coil of material is shown. The car runs on rails 74. The coiling means operates in the following way. The outer drum 1 or 41, is brought to rotate at such a speed that the coiling surface 2 or 42 will attain a peripheral speed which corresponds to the inlet speed of the press product 34 or 70. The press product will lay itself on the inner coiling surface 2 or 42. When the extrusion is finished, the outer drum continues to rotate but the supply of the press product ceases. The press product 34 or 70 is firmly connected with the residual billet in the pressure chamber, and its movement is therefore stopped instantaneously. The press product nearest the guide tube 33 or 71 is stretched, which means that the diameter is reduced and that it will lay itself around the inner drum and successively be completely coiled on this drum. The forces acting on the press product will be small and the risks of the product being damaged, for example by flattening, stretching or tearing, are eliminated. When the product has been cut off at the press outlet, the inner drum is started, and the part of the press product which is located between the drum 15 or 52 and the press is coiled on. After this, the coil of material is removed. In the embodiment according to FIG. 1, the inner drum 15 is lifted up by means of the lifting device 27, the car 31 is run in under the drum and the supporting members 26 are released, en-

abling the coil to fall down freely on to the car 31. In the embodiment according to FIG. 2, the coil supports 65 are retracted with the help of the operating devices 69 and the coil falls down on the car 73.

I claim:

1. Method of coiling strip-formed material which comprises leading the material tangentially into and coiling it inside a first hollow drum rotating at such a speed that its peripheral speed is substantially the same as the speed of the material, suddenly ceasing the supply of material, and thereafter coiling the material around a second drum arranged inside the first drum, said second drum being stationary or rotating at a low speed.

15 2. Means for coiling strip-formed material comprising a first hollow rotatable drum having an inner coiling surface and a second drum within the first drum and spaced therefrom having an outer coiling surface, means mounting said drums for rotation about substantially coincident axes, said drums providing a space therebetween opening axially into the space between the drums, means for guiding strip-formed material into such space against the inner surface of the first drum independently of the drums, and means to rotate the first and second drum independently of each other.

3. Means as claimed in claim 2, in which the drums rotate about a vertical axis and the outer drum has upper and lower parts, and the guiding means guides the material substantially tangentially against the inner surface of the upper part of the first drum.

30 4. Means as claimed in claim 3, in which the first drum is conical.

5. Means as claimed in claim 4, in which the lower part of the first drum has the largest diameter.

6. Means according to claim 5, in which the first drum is provided at its lower part with inwardly projecting supporting members for the coiled-up material preventing the material from falling out of the drum.

7. Means according to claim 6, in which the second drum is provided with movably arranged supporting members for a coil, which supporting members are collapsible or retractable so that a coil on the second drum can unimpededly pass the supporting members axially.
